CONTINUOUS MINING MACHINE HAVING AN ANGULARLY ADJUSTABLE CUTTER HEAD

James S. Robbins, St. Paul, Minn., assignor to Goodman Manufacturing Company, Chicago, Ill., a corporation of Illinois

Continuation of application Serial No. 387,441, October 21, 1953. This application June 7, 1956, Serial No. 590,065.

1. Claim. (Cl. 262—7)

This invention relates to improvements in mining machines of the multiple boring arm type adapted to cut contiguous bores in advance of the machine. Such machines, commonly known as McKinlay type miners, have a cutter head including a pair of laterally spaced, radial boring arms and auxiliary horizontally disposed upper and lower cutter bars, which follow immediately behind the boring arms to modify the circular bore pattern by producing flat floor and roof surfaces.

One of the principal objects of the present invention is to provide a machine of the type above mentioned, wherein the cutter head is readily adjustable for vertical or lateral tilting angles with respect to its mobile base frame to increase its flexibility and maneuverability in mining operations.

A further object is to provide an improved and simplified structure, wherein the cutter head, the cutter head drive motors, and the discharge conveyor are formed as an integral unit for bodily adjustment relative to the mobile base frame.

A still further object of the invention is to provide an improved three-point mounting for the cutter head and its associated parts, to facilitate their adjustment relative to the base frame.

The present application is a continuation of my application Serial No. 387,441, filed October 21, 1953, now abandoned.

The invention may best be understood by reference to the accompanying drawings, in which—

Figure 1 is a side view of a mining machine made in accordance with the present invention;

Figure 2 is an exploded perspective view, with certain details omitted, showing the adjustable support for the rear end of the cutter head conveyor assembly which consists of a pair of hydraulic jacks;

Figure 3 is an enlarged fragmentary detail section taken generally on line 3—3 of Figure 1; and

Figure 4 is a diagrammatic view of the fluid control system for the hydraulic jacks shown in Figure 2.

Referring now to details of the embodiment of the invention shown in the drawings, a mobile base frame, indicated generally at 9, is mounted on parallel endless treads 10, 10. Said base frame has a relatively low-slung cross member 11 between the endless treads and forms, with said treads, an open longitudinal trough-like space for the reception of the cutter head conveyor assembly, as will presently be described in greater detail. The base frame carries suitable drive motors (not shown) for the endless treads, together with conventional control devices for operating them in unison or at different speeds or in opposite directions for maneuvering the machine, as usual, on the mine floor.

A cutter head, indicated generally at 12, includes a relatively large upright subframe 13 which carries a pair of forwardly projecting boring heads 14, 14 of conventional form including a plurality (herein three) of radial arms 15. The boring heads 14 are journaled, as usual, in the subframe 13.

2

A pair of horizontal, vertically spaced cutter bars 20, 21 are mounted along the top and bottom edges, respectively, of the cutter head subframe 13 immediately to the rear of the boring heads, to form guides for an endless cutter chain 22 provided, as usual, to remove the depending and upstanding cusps left by the two boring heads as they are advanced into the working face.

Other details of the boring heads and cutter chain mounted on the subframe 13 need not be described herein, as they form no part of the present invention.

The cutter head subframe 13 forms the sole support for motor-drive means for the two boring heads 14. Said motor drive means herein consists of similar but separate electric motors 35, 35 mounted integrally with gear reduction casings 35a secured to the rear of the subframe 13. Details of the gear reduction mechanism, and the gears for driving the boring heads, are not shown herein, as they form no part of the present invention.

An endless conveyor, indicated generally at 37, is rigidly connected to the subframe 13, so as to form therewith a separate cutter head conveyor assembly which is supported for bodily adjustment relative to the mobile base frame 9, as will now be described.

The illustrative means herein shown for adjustably supporting the front end of the cutter head conveyor assembly for either lateral or longitudinal tilting relative to the mobile base frame 9 includes a pair of laterally spaced, upright trunnion supports 38, 38 at the front end of the base frame 9, which trunnion supports carry inwardly projecting trunnion pins 39, 39 journaled in bearings at opposite sides of the cutter head subframe 13. As shown in Figure 3, each trunnion pin 39 is mounted eccentrically of an annular hub 41 journaled in the inner side of a housing 43 forming part of the upright trunnion support 38. The hub 41 is integral with a gear 44 in housing 43, which gear may be rotated manually by a ratchet handle 45 through a suitable reduction gear train, herein consisting of a small pinion 46 on stub shaft 47, herein shown as having its inner end journaled on needle bearings within the gear 44 and its hub 41. Said pinion 46 is meshed with a gear 48 fixed on another shaft 49 having a larger pinion 50 meshed with the aforesaid gear 44. In the form shown herein, the ratchet handle has a shaft 45a detachably connectable in a socketed end 47a of the stub shaft 47, so as to permit said ratchet handle to be removed from the machine when not in use.

Each of the trunnion pins 39 has a partially spherical bearing sleeve 51 rotatably and slidably mounted thereon, and engaged in a correspondingly shaped bearing ring 52 fitted in the side of the subframe 13, as shown in Figure 3, so as to provide, in effect, a universal or ball joint for each of the two trunnions, thereby permitting the subframe to assume varying angles, and to tilt on varying axes, relative to the base frame 9. The slidable mounting of the bearing sleeves 51 on trunnion pins 39 permits limited endwise movement of said sleeves to compensate for any increase in distance between the trunnions and the subframe due to varying adjustments of said trunnion pins.

It will now be understood that the two trunnion pins 39, 39 are each adjustable in a circle so as to vary the position of the axis of lateral or longitudinal tilting movement of the subframe 13 relative to the base frame 9, as may be desired to counteract "spiraling" of the cutter head, or to make other minor corrections in lateral or up-and-down steering of the machine while it is in use. For instance, if the machine starts to "spiral," i. e. cut upwardly on one side and downwardly on the other, one side of the head may be lifted and the other side lowered by moving the proper trunnion pin to a higher position and the other to a lower position. Similarly, minor corrections in steering can be made by adjusting one of

the trunnion pins to a more forward position and the other to a more rearward position. Smaller adjustments can, of course, be made by adjusting only one of the trunnion pins.

It will be further understood that the adjustment of one or both trunnion pins 39, as above described, also permits the cutter head-conveyor assembly to tilt bodily longitudinally of the machine about varying transverse axes, depending upon the relative adjusted positions of the two trunnion pins.

The conveyor 37 has a generally U-shaped frame 55 supporting an endless flight type chain conveyor of any well-known construction. Said conveyor frame is rigidly secured at its front end near the bottom of the cutter head subframe 13, and extends at an upwardly and rearwardly inclined angle, so that the chain conveyor receives loose material at the floor immediately to the rear of the lower cutter bar 21, and carries it for discharge into any suitable material-transporting apparatus, such as another conveyor, shuttle car, or the like. In the form shown herein, the conveyor frame 55 is made of substantial strength, so as to provide a support for the rear end of the cutter head-conveyor assembly rearwardly of the trunnion pins 39, 39. A drive motor 56, having suitable chain drive connections with the rear end of the flight conveyor, is also supported below the rear end of the conveyor frame and forms a part of the cutter head-conveyor assembly.

Figures 1 and 2 show the mechanism for tilting the cutter head-conveyor assembly longitudinally of the machine about a transverse axis, herein provided by the trunnion pins 39, by means of a pair of hydraulic jacks 75, 75. Said jacks each have double-acting pistons 76, the lower ends of which pistons are connected by ball joints 77 to brackets 78 fixed in laterally spaced relation on the cross member 11 of base frame 9. The upper ends of the jacks 75 are connected by ball joints 79 to opposite sides of the conveyor frame 55.

The hydraulic control system for the motor devices 75 is shown diagrammatically in Figure 4, wherein a pump 80, which may be either motor or hand-operated, is connected by line 81 to a control valve 82 of any well-known construction designed to supply pressure selectively to lines 83 and 84, respectively, leading by cross connecting lines 85 and 86 to the upper and lower ends of both hydraulic jacks 75, 75. As usual, when pressure is supplied to one of the lines, the other line is opened for pressure relief through a line 87 connecting valve 82 to low pressure tank 88.

By reason of the cross-connection of the upper and lower ends of jacks 75 through lines 85 and 86, as just described, it will be observed that the pistons in the two jacks are free to accommodate themselves automatically to any lateral tilting adjustments of the cutter head-con-

veyor assembly, so as to provide, in effect, a three-point suspension of the cutter head-conveyor assembly, and the ball-jointed mounting of both upper and lower ends of the hydraulic jacks permits the superposed assembly to shift forwardly or rearwardly as may be necessary to accommodate for forward or rearward adjustment of the trunnion pins 39.

It will be especially observed that the hydraulic jacks 75, 75, with their cross-connecting fluid lines 85 and 86, will permit the cutter head-conveyor assembly to be tilted laterally relative to the base frame 9 on varying transverse axes defined by the adjustable trunnion pins 39, 39.

The use and operation of the machine will now be manifest to those skilled in the art. Adjustment of the trunnion pins 39 can be readily effected, when necessary, to offset any spiraling of the cutter head, and also to effect any minor corrections in steering of the cutter head as it is being driven into the working face. The frame 55 of the endless conveyor 37, together with the parts suspended from the rear end thereof, such as the conveyor drive motor 56, are spaced a sufficient distance from the endless treads 10, 10, so as to afford sufficient clearance for any permissible tilting or lateral swinging adjustments of the cutter head-conveyor assembly as a whole.

Although I have shown and described a certain embodiment of my invention, it will be understood that I do not wish to be limited to the exact construction shown and described, but that various changes and modifications may be made without departing from the spirit and scope of the invention as defined in the appended claim.

I claim:

In a boring machine, a mobile main frame, an auxiliary frame having a boring head thereon for forming a bore in advance of the machine, supporting means adjacent the front of the machine affording tilting of said auxiliary frame laterally and longitudinally relative to said main frame, and means disposed rearwardly of said support means for supporting said auxiliary frame for lateral and longitudinal tilting on said main frame comprising a pair of laterally spaced generally upright hydraulic jacks flexibly connected for lateral rocking movement between said auxiliary and main frames, and hydraulic pressure means for extending or retracting said jacks including pressure and relief lines each connected to similar ends of said jacks from a fluid line common to said similar ends, to permit interchange of fluid between similar ends of said jacks to accommodate said jacks to lateral tilting of said auxiliary frame, in various positions of extension or retraction of said jacks.
